B. BRIDENDOLPH.

Hominy Machine.

No. 11,547.

Patented Aug. 22, 1854.

UNITED STATES PATENT OFFICE.

BENJAMIN BRIDENDOLPH, OF CLEAR SPRING, MARYLAND.

HOMINY-MILL.

Specification of Letters Patent No. 11,547, dated August 22, 1854.

To all whom it may concern:

Be it known that I, BENJAMIN BRIDENDOLPH, of Clear Spring, in the county of Washington and State of Maryland, have 5 invented a new and useful Improvement in Hominy-Mills; and I do hereby declare that the following is a full, clear, and exact description of the construction and operation of the same, reference being had to the annexed drawings, forming part of this specification, in which—

Figure 1 is a vertical section of the mill, taken through the axis of the hulling shaft, and perpendicular to the fan shaft. Fig. 2 15 is an elevation of the hulling shaft. Fig. 3 is an elevation of the interior of the concave.

Similar characters of reference in the several figures denote the same part of the machine.

20 The nature of my invention consists in the peculiar construction of the hulling shaft, which is of a compound spiral form, the edges of the main spirals being traversed by a series of short spirals running in the reverse direction; this shaft being revolved within a roughened cylinder and by the action of the two series of spirals upon the corn, effectually stripping the grains of hulls and eyes, and breaking the 25 same to the required size, in the manner hereafter to be described.

To enable others skilled in the art to make and use my invention I will proceed to describe its construction and operation.

30 In the drawing A is the cylinder supported by the frame B and having its interior surface made up of the small pyramidal projections *c* so as to present a roughened surface with innumerable salient edges, disposed in the best manner for assisting in the stripping and breaking operation. The hulling shaft C is of the form shown in Fig. 2, having the hollow spiral faces *d* meeting along edges, across which run the 35 spirals *f* in the reverse direction from the main spirals *d*. This shaft rests in the bottom of the cylinder A, and is revolved by power applied to the shaft *e* through the bevel wheels *h* and *i*. In the bottom of the 40 cylinder A is the sliding door *m* through which the hominy issues to the screen S where it is cleaned of hulls and other light impurities by the fan *n*.

The operation of my improved hominy mill is as follows: The corn is fed to the 55 machine by the hopper H and motion communicated to the shaft C as above described. A band around the pulley P and fan shaft gives motion to the fan, and reciprocates the sieve *s* through the rods *t* and *u*, and 60 crank *v*. The spring door *m* is kept closed at first and opened but slightly after the operation has progressed, for the passage of the finished hominy. The main spirals *d* of the hulling shaft, tend by the revolution 65 of the shaft to pack the corn in a mass toward the bottom of the cylinder; while the reverse spirals *f* on the edges, catch the downward pressed grain, and draw it upward against the roughened interior of the 70 cylinder, causing a severe cutting friction sufficient to strip off the hulls, remove the eyes, and break the grain. The main spirals *d* having a greater action than the secondary spirals *f*, the corn is always crowded in a 75 mass to the bottom of the cylinder, and is always in a situation to receive the reverse action of the spirals *f*. The door *m* is opened slightly, so that the finished hominy shall pass out slowly and not prevent 80 the packing of the mass in the bottom of the cylinder. After leaving the cylinder, the fan and screen separate, the impurities in the ordinary manner.

The important feature of this mill is the 85 compound spiral hulling shaft, the main spirals of which pack the body of the corn sufficiently hard for the reverse spirals to effectually act upon, and by the aid of the roughened concave to break and strip the 90 grain.

What I claim as my invention and desire to secure by Letters Patent, is—

The compound spiral hulling shaft constructed as herein described, and operating 95 in connection with a roughened concave for hulling and breaking corn substantially as specified.

In testimony whereof, I have hereunto signed my name before two subscribing witnesses.

B. BRIDENDOLPH.
